HUGO H. VOSS, OF CHICAGO, ILLINOIS, ASSIGNOR TO MAYER'S MOBILE MERCHANT DISER, A COPARTNERSHIP CONSISTING OF MILTON M. MAYER AND ROBERT T. MACK, OF CHICAGO, ILLINOIS

MOVABLE SIGN

Application filed April 5, 1928. Serial No. 267,741.

This invention relates to new and useful improvements in movable signs, and has for its object the provision of a continuous message display, utilizing exhibit space exceeding in area the exhibition space normally available in a given length.

With the above and other objects in view, as will be apparent, this invention consists in the construction, combination and arrangement of parts, all as hereinafter more fully described, claimed and illustrated in the accompanying drawings, wherein:

Fig. 1 is a front elevation of a cabinet for housing a movable sign embodying this invention, and illustrates the portion of a message visible to an observer when the sign is in operation;

Fig. 2 is a horizontal section, partly in elevation, taken along line 2—2 of Fig. 1, to show the assembly of parts;

Fig. 3 is a horizontal section taken on line 3—3 of Fig. 1;

Fig. 4 is a vertical section taken along line 4—4 of Fig. 2, illustrating the mounting of the sign units and the driving mechanism therefor;

Fig. 5 is a vertical section taken on line 5—5 of Fig. 2, and illustrates the pivotal mounting of the sign units;

Fig. 6 is a fragmentary horizontal section taken on line 6—6 of Fig. 4, showing details of the mechanism for reversing the sign units;

Fig. 7 is an irregular vertical fragmentary sectional view taken on line 7—7 of Fig. 2, showing a series of sign units in operative position and illustrating the position of one of the units in the process of reversal;

Fig. 8 is a perspective view of a sign unit showing the details thereof; and

Fig. 9 is a horizontal section taken on line 9—9 of Fig. 7, through one of the sign units, disclosing the mounting of the letter or exhibition panels.

In an advertising device of the general type comprising a movable message or display, it is desirable to produce a message or display of maximum length within a limited space. To this end it is necessary to provide means for increasing the available exhibition space in a manner to accommodate a series of mes-

sages or a message having a length exceeding that obtainable under normal conditions, to wit, a single exposed exhibition area. This result is accomplished in the present invention by providing moving chains carrying a series of reversible sign units, each of said sign units bearing, on each face thereof, a portion of a message or display, which portions combine to present a whole message or display. After this series of sign units bearing a portion of a message or display have successively passed a predetermined point of exposure to observation, and having thus displayed a message or portion thereof, each of said series of units is successively reversed at a point removed from observation, preparatory to redelivering said series of units to the aforesaid predetermined point of exposure for presenting to view the previously unexposed portions of a message or display. If desired, the corresponding faces of the said sign units may bear two separate and distinct messages or displays whereby the initial exhibit will present one message or display while the successive reversal and subsequent exhibition of the sign units creates a new and different message or display.

Reference being had more particularly to the drawings, H represents a housing or cabinet in which the device forming the subject matter of this invention is mounted. This cabinet H has a base B and a top T, between which are mounted two vertical parallel shafts 10 and 10'. These shafts 10 and 10' are spaced apart and located at opposite ends of the base B and top T aforesaid, in the approximate longitudinal center thereof. Each of said shafts 10 and 10' have a pair of sprockets 13 secured thereto and so spaced that the sprockets are mounted near the respective extremities of the shafts 10 and 10'. A standard electric motor M is mounted on said base B in a convenient location and said motor is operated to drive the shaft 10, which is provided with a spiral gear 12 adapted to engage a similar gear 11 on the shaft of the motor, as shown in Figs. 2, 3, 4 and 7. By reason of said gears 11 and 12, the motor M rotates the shaft 10 to turn the sprocket 13 mounted thereon.

An endless chain C coacts with each pair of coplanar sprockets 13 and extends from one end of the cabinet H to the other. As the shaft 10 is driven, the superposed chains C are operated by the sprockets 13 and the idler shaft 10' is thus driven. The links forming said chains C have projecting pins 14 extending downwardly from the upper chain C and upwardly from the lower chain C. These pins 14 are designed to constitute pivots for the mounting of the sign units S, to be hereinafter more fully described, and to that end each pair of superposed pins 14 are aligned vertically, one with the other, and the chains 15 C are so placed on the sprockets 13 for this purpose.

Sign units S for arranging the letters or other display matter forming an exhibition as herein contemplated, are provided, one of which is shown in detail in Fig. 8 and in end cross section in Fig. 9. This unit S comprises a rectangular plate having a trunnion 16 at each end thereof and aligned longitudinally therewith. Each of these trunnions 16 has a socket 17 therein, which is adapted to receive one of the pivot pins 14, whereby the sign unit S is pivotally mounted between a pair of said pins 14 and between the chains C. The lower trunnion 16 of each sign unit S 30 carries a spur gear 18 by means of which the unit is oscillated or reversed, as will be described more fully hereinafter. In order to removably attach sign panels 19 to the opposed faces of the sign unit S, each face thereof 35 is surrounded by a flange 20 outstanding from said sign unit S, which at its outer edge terminates in a lip 21 thereby forming a groove 21' upon three sides of each face of the sign unit S, said groove 21' being open at their upper ends to permit insertion of panels 19, bearing the display matter forming the message or slogan to be shown. It is to be observed that if desired, only the two longitudinal sides of the sign unit S need be provided with grooves 21' so that the edge of the panel 19 will merely rest on the lower flange 20 and be held by the lips 21 at the sides of said sign unit S.

In order to prevent the sign units S from 50 moving out of the desired alignment as they travel through the cabinet, a guide channel 22 is fixed on the base B coextensively with the course of movement of the chains C. As will be noted in Figs. 4 and 5, where the guide channel 22 is shown in section, the upright webs of said channel 22 cooperate and contact against both sides of the lower edge of the sign unit S, while the bottom or horizontal portion of the channel is adapted to act as a bearing surface for the under-side of the moving chain C. In this manner, throughout the major portion of the movement of the chain C, the sign units S are so engaged by the channel 22 that the units are not permitted to have any pivotal movement. However, in

order to successively reverse the units, the channel is cut away as at 23, in Fig. 6, for a distance slightly greater than the width of the sign unit S to permit the edges of the sign unit to have a safe clearance from obstruction in the reversing operation. It will also be noted from Fig. 6, wherein an arrow indicates the direction of movement of the sign units S, that the guide channel 22 has a flared entrance to facilitate the movement of the unit S into the guide channel 22 as it continues its course of movement subsequent to the reversal operation. 70 75

To successively reverse the units S, a fixed rack R is mounted on the base B by means of a bracket 27 positioned between the terminals of the channel 22 and adjoining the path of movement of the units S, as illustrated in top cross-sectional view in Fig. 6. The teeth of said rack member R successively engage the spur gears 18 carried by the lower trunnions 10 of the sign units S. In operation, as the sign unit S is delivered by the movement of the chains C, to the space 23, the spur gear 18 80 85 coacts with the teeth of the rack R and imparts a half turn to the unit S to obtain a reversal of its position preparatory to its next passage through the machine, all without any interruption in the movement of the chains C. 90 95

The sign units S are preferably of a size to allow a series thereof to be viewed simultaneously through the opening 24 in the front wall of the housing H, illustrated in Fig. 1. By thus allowing several sign units to appear simultaneously, it is possible to maintain in view at any given time, two or three words each of an average number of letters, as Fig. 1 discloses. As the chains C travel through the cabinet H, one surface of each sign unit S successively travels across the opening 24 and is there exhibited. After this has been accomplished, the sign units S are successively reversed and the opposite or unexposed sides thereof are then successively exhibited through and across the opening 24, this operation and reversal being continuous. Thus the matter appearing on one surface comprising the respective sides of the entire series of sign units S combine to form one message or display, and subsequently the opposite surface comprising the corresponding previously unexposed sides of the whole series of sign units S combine to make another message or display, after which the sides initially shown are again presented. 100 105 110 115

It is, of course, understood that the opposed sides of the sign units may form two separate or distinct messages or may form one continuing message, whichever is desired. 120 125

If each of the sign panels 19 bear a letter, words can be built up by inserting the panels bearing appropriate letters, in the grooves 21' of the unit S, with blank panels to designate the spaces between the words. As the 120 125

units S are conveyed across the opening 24 for viewing the message to be presented, the letters successively appear from the right hand end of the opening as in Fig. 1, until the entire word is exhibited. As the sign units successively pass to the left and out of view, they are reversed, and when they again appear at the right side of the opening 24, a second series of letters and words appear as a result of a different combination of letters carried by the previously unexposed sides of the units S.

Longitudinal beveled strips 25 and 26 are respectively disposed interiorly above and below the opening 24, to conceal from view the chain and pivot mechanism supporting the sign units, as they travel across said opening 24.

To illuminate the sign, lamps L secured in the rear of the beveled strips 25 and 26 surrounding the opening 24, are adapted to cast light on the outer faces of the units S as the same are brought to view in the opening 24.

From the foregoing it is manifest that the present invention affords a type of advertising device for producing and movably exhibiting a continuous unitary message or display on a given length of surface having a uniformly flat solid contour, with facilities for automatically obtaining a greater exhibition space than is normally available in said length, for the purpose of accommodating a unitary message or display of maximum length, and at the same time maintaining a surface of a uniformly flat solid contour relative to the message or display while on view.

It is further characteristic of the present sign that the matter contained on the panels 19 may be varied and for this purpose the elements of the sign may be readily and quickly changed at will to present a variety of messages and words. A supply of panels 19 adds to the adaptability of the sign and its uses.

What is claimed is:

1. The combination with a flexible sign element comprising a series of sign units, each sign unit consisting of a rectangular plate having opposed faces, a flange surrounding each of said faces at its lower and longitudinal sides, said flange terminating in a lip to form a groove for removably holding a panel bearing display matter, of a housing enclosing said element and having an exhibition opening therein, means for continuously moving said sign element across said exhibition opening, said sign units occupying coplanar positions when passing across said exhibition opening and combining in a relationship to form a unitary sign, and means for reversing said units after passing said opening whereby they combine to form a new unitary sign.

2. The combination with a flexible sign element comprising a pair of superposed endless conveyors, of a series of sign elements, co-

operating with said conveyors, each unit having a trunnion at each end thereof for pivotal engagement with said conveyors, one of said trunnions being provided with a spur gear, a housing inclosing said conveyors and sign units, being provided with an exhibition opening in one side thereof, means for continuously moving said conveyors across said exhibition opening, said sign units at that point being so related one to the other that they combine to constitute a unitary sign, and means in the path of movement of said conveyors at a point remote from said exhibition opening for successively engaging the spur gears aforesaid to pivotally and successively move said sign units whereby other faces of said sign unit are presented in the exhibition opening to combine to form a unitary sign.

3. The combination with a flexible sign element comprising a pair of superposed chains, of means for operating said chains in unison consisting of a pair of vertical shafts, a sprocket mounted near the respective extremities of each shaft, each pair of sprockets co-acting with one of said endless chains, means for driving one of said shafts, a series of sign units interposed between said chains and having pivoted connection therewith, each sign unit including on each of its several faces an alphabetical or numerical character, of a housing including said element and having an exhibition opening in one side thereof, means for continuously moving said sign element to display said sign units through said exhibition opening, said sign units being so related one to the other when positioned in said opening that the characters on the faces thereof combine to constitute a unitary moving message, and means for operating said sign units about their pivots at a point in the path of movement of said sign element removed from said exhibition opening, to successively present the several sides of said units.

4. The combination with a flexible sign element comprising a pair of superposed chains, of means for operating said chains in unison consisting of a pair of vertical shafts, a sprocket mounted near the respective extremities of each shaft, each pair of sprockets co-acting with one of said endless chains, means for driving one of said shafts, a series of sign units interposed between said chains and having pivoted connection therewith, each sign unit including on each of its several faces an alphabetical or numerical character, of a housing including said element and having an exhibition opening in one side thereof, a guide for preventing pivotal movement of said units during the major portion of the path of movement of the chains, said guide consisting of a channel having upright webs adapted to cooperate with and contact against both sides of the lower edge of the sign unit,

and having a bottom portion adapted to act as a bearing surface for the underside of the lower chain, and means at a point remote from the exhibition opening to coact with the sign units and successively reverse their positions, said guide being cut away to permit the rotation thereof.
